SOLENOID

Harold J. Luth, Muskegon, Mich., assignor to The Brunswick-Balke-Collender Company, Chicago, Ill., a corporation of Delaware

Application June 11, 1943, Serial No. 490,421

5 Claims. (Cl. 175—21)

1

This invention relates more particularly to extremely long and slender solenoids wherein the core and winding of the solenoid are not self-supporting.

The general object of the invention is to provide a solenoid of this type having a rigid, non-metallic shell or casing which can be constructed about the solenoid and serve as a means of support therefor.

A more particular object of the invention is to provide a rigid supporting structure for solenoids having high permeability cores and a high sensitivity which is affected by deflection of the assembly.

Another object of the invention is to provide a novel method whereby such a rigid casing can be constructed about the solenoid. Another object of the invention is to provide a solenoid with a rigid and durable casing which will also protect the winding of the solenoid from mechanical injury, or injury due to the elements or from handling.

A further object of the invention is to provide a solenoid with a casing which becomes an integral part thereof.

Other objects will become readily apparent from the following detailed description, taken in connection with the accompanying drawing, in which:

Fig. 1 is an elevational view of a solenoid constructed in accordance with the invention.

Fig. 2 is an enlarged fragmentary view thereof, partly in central section.

Fig. 3 is a section along the line 3—3 of Fig. 2.

Fig. 4 is a view illustrating a method of making the form of the invention of Figs. 1 to 3.

Fig. 5 is an enlarged fragmentary view of a part of Fig. 4.

While there is illustrated in the drawing and herein described in detail a preferred form of the invention, it is to be understood that the invention is not to be limited to the particular form and arrangement shown, it being contemplated that various modifications may be made by those skilled in the art without departing from the spirit and scope of the invention as set forth in the appended claims.

In Figs. 1 to 3 of the drawing there is illustrated a solenoid having a high permeability core 10, ends 11, a winding 12, and a casing 13. In this form of the invention the casing 13 is wound in layers onto the solenoid winding and consists of several turns 14 of resin impregnated paper or cloth, several additional turns of impregnated paper or cloth with wood veneer 15 interleaved,

2

the grain of the wood veneer running lengthwise of the solenoid, and lastly, additional layers of impregnated paper or cloth, or both.

Preferably a high tensile spinning paper is used which has been impregnated with an amount of heat-setting phenol formaldehyde resin equal to about 35 percent of the weight of the paper. A heat-setting phenol formaldehyde resin which is soluble in a solvent such as alcohol or water, and which can be evaporated off, may be used for this purpose. A resin manufactured by the Bakelite Corporation and identified by their number XV16238 has been used successfully. By paper which has been impregnated is meant paper which may be coated on one side, or both sides, or entirely filled with resin. The veneer is preferably coated on two sides.

Fig. 4 illustrates the manner in which the casing 13 may be applied to the solenoid winding. A sheet of paper 14, coated with a suitable resin 20 (Fig. 5) on its upper side, has been wound onto the solenoid coil until there are several turns of the paper on the winding. Veneer 15 coated with resin on its surfaces at 21 has been placed upon the upper coated surface of the paper 14 in position so that as the winding of the paper onto the solenoid continues, there is placed on the solenoid several turns of veneer separated by the sheet of paper 14 which extends continuously to the end 22. As the winding operation continues, additional layers of resin coated paper are applied on top of the veneer-paper layers so that the outer portion of the casing consists of several layers of the paper. The entire assembly is then cured under heat and pressure, as by jacketing the assembly in a sheet of rubber which has been elongated from 150 to 200 per cent and applied under tension, and thereafter placed in an oven at a temperature of 250° F. for a period of two hours, utilizing the process disclosed in a co-pending application, Serial No. 483,540, filed April 19, 1943, by Harold J. Luth, Herman B. Scheidemantel and Sydney R. Krupnick.

In the event that the solenoid is to have an outer casing of cloth as described immediately hereafter, the squeezing effect obtained by jacketing the solenoid in rubber can be very nearly duplicated by tightly winding the last layer of cloth in a spiral under tension, securely fastening the two ends and then curing. During the curing operation the cloth jacket will tend to shrink and harden about the entire assembly, making the mass compact. Although this method can be used, for extreme rigidity and

hardness the method using a rubber jacket is preferred.

The solenoid constructed as herein disclosed is extremely rigid and adequately protected against mechanical injury or injury due to the elements or from handling. A solenoid constructed in accordance with the invention, 2½" in diameter and 6' long and containing 60 pounds of copper wire and core, has been wound with four turns of impregnated paper, followed by four complete turns of paper and veneer, six turns of paper and one turn of impregnated cloth on the outside. A solenoid so constructed and thereafter cured as hereinbefore specified, when supported at its two ends, had a deflection at the center on the order of $\frac{1}{16}$ of an inch. Under the method herein set forth the entire assembly becomes an integral unit and the solenoid is entirely self-supporting.

During the entire process the solenoid is preferably supported on a flat table or on parallel rollers or other suitable means which will prevent distortion or deflection until the curing and setting operations are completed.

In using phenol formaldehyde resins or cements, approximately 4% of an acid or alkaline catalyst is used to bring about the hardening. Although an adhesive or resin of the type hereinbefore set forth is satisfactory and desirable, it is not intended to limit the invention to the use of any particular resin or combining agent. It would be possible, for example, to make a similar solenoid casing by using urea formaldehyde bonding agents which are thermo-setting, or by using shellac which is thermo-plastic. In the case of a shellac, however, it would be necessary to cool the solenoid while it is hung in a vertical position.

As a veneer, birch and maple have been used. Obviously other types of wood and other low-density, high-tensile value materials might be used to make a casing having suitable rigidity. An impregnated cloth can readily be substituted for paper. If an extreme degree of waterproofness is desired, the veneer can first be treated by saturation with a phenol resin dissolved in alcohol, or by use of a hydrophilic resin in water in the same manner as wood is treated for impregnating wood, a process well known in the art. In the examples hereinbefore given, the paper was approximately .005 of an inch in thickness, and the veneer was .05 of an inch, the resulting casing being approximately $\frac{1}{8}$ of an inch thick.

I claim as my invention:

1. A solenoid comprising a core, an insulated winding thereon, means outside of said winding and surrounding it comprising a sheet of material impregnated with a heat-setting resin wound around the winding in layers, and a thin sheet of wood wound intermediate certain layers of said impregnated material and with its grain running parallel to the axis of the solenoid to reinforce

the solenoid and operating to stiffen the solenoid and prevent bending thereof when said means has been subjected to heat to cause the resin to set.

5 2. A solenoid comprising a relatively long metal core, a winding on said core comprising a plurality of layers of insulated wire and combining with the core to form an elongated element of substantial weight, and means for enclosing the winding and preventing flexure of the solenoid when supported in a horizontal position and by its ends, comprising a sheet of paper impregnated with a heat-setting phenol formaldehyde resin wound in tight layers over the outer layers of said winding and a sheet of resin impregnated thin wood reinforcing material wound between a plurality of layers of said paper with its fibers extending mainly lengthwise of the solenoid, said enclosing means being subjected to heat to cause the resin to set and operating to stiffen the solenoid and prevent bending thereof.

15 3. A solenoid comprising a long central core, an insulated winding around said core, and means enclosing the winding comprising a sheet of paper impregnated with a heat-setting phenol formaldehyde resin wound in tight layers over the outer surface of said winding, and a sheet of resin impregnated wood wound between consecutive layers of said paper with its fibers extending longitudinally of the solenoid and operating to stiffen the solenoid and prevent bending thereof when said enclosing means has been subjected to heat to cause the resin to set.

20 4. A solenoid comprising a long central core, an insulated winding around said core, and means enclosing the winding comprising a sheet of cloth impregnated with a heat-setting phenol formaldehyde resin wound in tight layers over the outer surface of said winding, and a thin sheet of reinforcing wood material wound between intermediate layers of said cloth and operating to stiffen the solenoid and prevent bending thereof when said enclosing means has been subjected to heat to cause the resin to set.

25 45 5. A solenoid comprising a relatively long cylindrical core, a winding on said core comprising a plurality of layers of insulated wire and of substantial weight, and means for enclosing the winding and preventing flexure of the solenoid when supported in a horizontal position and by its ends, comprising a sheet of thin sheet material impregnated with a heat-setting phenol formaldehyde resin wound in tight layers over the outer layer of said winding, and a sheet of wood wound between consecutive layers of said thin sheet material and operating to stiffen the solenoid and prevent bending thereof when said enclosing means has been subjected to heat to cause the resin to set.
